UNITED STATES PATENT OFFICE.

CHRISTOPHER SAMUEL DAVY, OF DULWICH, AND ARTHUR SPYER, OF LONDON, ENGLAND, ASSIGNORS TO THE BABCOCK & WILCOX COMPANY, OF BAYONNE, NEW JERSEY, A CORPORATION OF NEW JERSEY.

MECHANICAL STOKER.

Application filed July 6, 1921. Serial No. 482,718.

To all whom it may concern:

Be it known that we, CHRISTOPHER SAMUEL DAVY and ARTHUR SPYER, subjects of the King of Great Britain, and residing at 5 162 Rosendale Road, Dulwich, London, S. E. 21, England, and 14 Clarendon Court, Maida Vale, London, England, respectively, have invented certain new and useful Improvements in Mechanical Stokers, of 10 which the following is a specification.

This invention relates to improvements in and connected with mechanical stokers, and has for its object to improve the efficiency of a furnace fitted with such stokers by providing it with a simple and reliable means for effecting a controlled pressure air supply, and with mechanical means adapted, while the pressure air supply is in operation, to deal with the fuel riddlings and waste ash, 15 the arrangement preferably being such that the grate may be run simultaneously on natural draught, if required.

The invention is illustrated in the accompanying drawings in which Fig. 1 is a 20 longitudinal section, Fig. 2 a cross section and Fig. 3 a plan showing the apparatus applied to a chain grate stoker of the Babcock & Wilcox type, a part of the chain being removed, and Fig. 4 is a longitudinal 25 section of a modified form of apparatus.

In the arrangement shown in Figs. 1, 2, and 3, the apparatus is disposed between the upper and lower runs of the revolving chain of the mechanical stoker, while in the arrangement shown in Fig. 4, part of the apparatus is disposed between the runs of the revolving chain, and part disposed on the outside of the bottom and front portion of the revolving chain.

Referring to the drawings, it will be seen that a plurality of chambers or compartments A for distributing the air under pressure, are provided, but there may be only one chamber, or one chamber may be divided into as many chambers as thought necessary, according to the installation. The air under pressure is supplied from the main trunk A⁴, through branches A³, all of which have openings A² into the chambers A. The 45 branches A³ are fitted with dampers A⁵ to regulate the air pressure in the chambers A. After the air is supplied to chambers A the air distributes itself to the underside of the 50

fuel bed which is carried on the revolving chain B, by means of openings A⁶, through 55 the chain grate, the openings in the upper run of the chain grate B above the chambers A being in communication therewith.

Preferably arranged lengthwise of the stoker is a revolving valve C, the seat of 60 which has openings C¹ and C². The opening C¹, being always open to the inside of chambers A, allows the riddlings to be blown into the valve C and delivered through the outside side openings C² of the valve body. The 65 valve member C is preferably provided with a plurality of radial vanes, here illustrated as four in number, so arranged that two opposite vanes always engage the valve seat, thereby always maintaining the air chamber 70 or chambers sealed. Valve C is driven mechanically by means of a rotating shaft C³ from a geared wheel C⁴, the latter being driven by the geared wheel D¹, which is rotated by a countershaft D, the countershaft 75 D being driven from the front chain grate, driving shaft E by means of bevel wheels E¹ and E². The force of the entering air carries the riddlings transversely over the plate A¹³, located above the lower run of 80 the chain to the rotary discharge member which is sealed against said plate. The riddlings are thus collected in the pockets formed between the vanes of the rotary member which discharges them through the 85 opening C², from which they are deposited on the lower run of the chain and either sift therethrough or are carried to the forward end of the grate where the surface of the chain is broken thereby forming openings 90 between adjacent links in passing over the front sprocket wheels, forming openings through which the residual riddlings fall.

The valve may be fitted either parallel to the axis of the chambers A, as in Figs. 1 and 95 2, or transverse thereto as in Fig. 4.

In Fig. 4 is shown an alternative arrangement of pressure draught and riddling deposit apparatus, part of which is placed within the revolving chain grate B, and part 100 below the bottom and front side of chain grate B.

In this figure only one pressure air chamber A₁ is shown, but this may be divided into several compartments, and the high pressure 105 air supply may enter into the said chambers

by any suitable place or places, according to the installation required.

To render air chamber A, suitable for high pressure air draught, and at the same time to deal with the riddlings and waste ash, sealing plates A⁷ and A⁸ are arranged behind the front driving shaft and in front of the rear shaft. A plate A⁹, disposed below the underside of chain B of the stoker, is connected up by plates A¹⁰ and A¹¹ and a door A¹² to the stoker hopper, the door being placed at the front for inspection, or for running on natural draught. In the form shown in Fig. 4, the riddlings pass through the lower run of the chain grate and are carried along on the plate A⁹ until they are discharged into the valves C⁵.

To the plates A⁷ and A⁸ are attached the plates F and F', which lie on the upper side of the bottom portion of the chain B, thereby effecting an air seal with the bottom plate A⁹.

The pressure air supply chamber A delivers and distributes its air equally through the openings A⁶ into the fuel bed which is carried on the upper surface of the chain B.

The plate A⁹ serves a further purpose, viz, to divide and deliver the riddlings from the waste ashes which fall through the chain grate, while the latter is in operation, to their respective destinations. For this purpose the plate A⁹ is divided into three parts, to which are fixed two revolving valves C⁵ adapted to be driven from the driving shaft of the chain grate stoker.

The plate A⁹ with its valve C⁵ at the rear of the stoker collects and delivers ash through the valve C⁵ into the ash-pit G. The center plate A⁹ collects all the riddlings which drop through the grate B and are carried forward by the bottom chain B until they reach the front valve C⁵, where they are delivered by said valve C⁵ into the riddling pit H, from which they are carried back for refiring onto the stoker.

What we claim and desire to secure by Letters Patent of the United States is:—

1. In combination, a chain grate stoker, a compartment associated therewith communicating with the under side of the upper run of said chain grate, means for supplying air under pressure to said compartment, and a discharge member associated with said compartment constructed and arranged to discharge riddlings therefrom and maintain the compartment sealed during operation.

2. In combination, a chain grate stoker, a compartment associated therewith communicating with the under side of the upper run of said chain grate, means for supplying air under pressure to said compartment, and a discharge member associated with said compartment and actuated by the grate-driving mechanism for discharging rid-

dlings from said compartment and constructed and arranged to maintain the said compartment sealed during normal operation.

3. In combination, a chain grate stoker, a compartment associated therewith communicating with the under side of the upper run of said chain grate, means for supplying air under pressure to said compartment, and a rotary discharge member associated with said compartment for discharging riddlings therefrom, and constructed and arranged to maintain said compartment sealed during operation of said member.

4. In combination, chain grate stoker, a compartment associated therewith communicating with the under side of the upper run of said chain grate, means for supplying air under pressure to said compartment, a valve member comprising a rotary valve actuated by the grate-driving mechanism and provided with a plurality of radial vanes, and a valve seat for said valve provided with discharge openings for discharging riddlings from said chain grate, the valve member being constructed and arranged so that opposite vanes always engage said valve seat to maintain said compartment sealed.

5. In combination, a chain grate stoker, a compartment located between the upper and lower runs of said stoker and communicating with the lower side of the upper run, means for supplying air under pressure to said compartment, and a discharge member associated with said compartment constructed and arranged to discharge riddlings therefrom and maintain the compartment sealed during operation.

6. In combination, a chain grate stoker, a compartment located between the upper and lower runs of said stoker and communicating with the lower side of the upper run, means for supplying air under pressure to said compartment, a discharge member located at one side of said compartment sealed during normal operation and constructed and arranged to discharge riddlings from said compartment and maintain the compartment sealed during operation, and means for admitting air under pressure to the side of said compartment opposite said discharge member.

7. In combination, a chain grate stoker, a compartment located between the upper and lower runs of said stoker and communicating with the lower side of the upper run and comprising a plate located above the lower run of the chain grate, means for supplying air under pressure at one side of said compartment and grate, a discharge member located at the other side of said grate extending longitudinally thereof and sealed against said plate, said member being constructed and arranged to discharge riddlings from

said compartment and at the same time maintain said compartment sealed during operation.

8. In combination, a chain grate stoker, a compartment located between the upper and lower runs of said stoker and communicating with the lower side of the upper run and comprising a plate located above the lower run of the chain grate, means for supplying air under pressure at one side of said compartment and grate, a rotary discharge mem-

ber located at the other side of said grate extending longitudinally thereof and sealed against said plate, said member being constructed and arranged to discharge riddlings from said compartment and at the same time maintain said compartment sealed during operation. 15

In testimony whereof we have hereunto signed our names.

CHRISTOPHER SAMUEL DAVY.
ARTHUR SPYER.
